(57) CLAIM

What is claimed is an ornamental design for a soft-sided cooler, as shown and described.

DESCRIPTION

FIG. 1 is a perspective view of a soft-sided cooler showing the design;

FIG. 2 is a front plan view of the soft-sided cooler of FIG. 1;

FIG. 3 is a rear plan view of the soft-sided cooler of FIG. 1; FIG. 4 is a left side plan view of the soft-sided cooler of FIG. 1;

FIG. 5 is a right side plan view of the soft-sided cooler of FIG. 1;

FIG. 6 is a top plan view of the soft-sided cooler of FIG. 1; and,

FIG. 7 is a bottom plan of the soft-sided cooler of FIG. 1.
